UNITED STATES PATENT OFFICE.

HENRY MUELLER, OF DECATUR, ILLINOIS, ASSIGNOR TO H. MUELLER MANUFACTURING COMPANY, OF DECATUR, ILLINOIS, A CORPORATION OF ILLINOIS.

ROTATABLE INDEX FOR COCKS.

950,187.

Specification of Letters Patent. Patented Feb. 22, 1910.

Application filed June 24, 1907, Serial No. 380,582. Renewed December 9, 1909. Serial No. 532,253.

To all whom it may concern:

Be it known that I, HENRY MUELLER, a citizen of the United States, and resident of Decatur, Macon county, State of Illinois, 5 have invented certain new and useful Improvements in Rotatable Indexes for Cocks; and my preferred manner of carrying out the invention is set forth in the following full, clear, and exact description, terminating 10 with claims particularly specifying the novelty.

This invention relates to cocks adapted for use with hot or cold water, or with other liquids of different kinds, and the object 15 is to provide for indicating either of a plurality of uses for which the cock may be adapted.

The invention is embodied in a rotatable index member, normally held against rotation between two clamping surfaces formed in or on the cock, and provided with different indications, such as words or signs, at 20 different places around its perimeter. The mode of operation is to loosen the clamping 25 pressure on the index member, to rotate the latter until the indication descriptive or suggestive of the desired use of the cock is presented in proper position for ready observation, and to then retighten the clamp.

30 The invention is exemplified in the structure hereinafter described, and it is defined in the appended claims.

In the drawings forming part of this specification, Figure 1 is a front elevation of 35 a right-and-left basin cock of the "Fuller" type, said cock being provided with two index members, one in the body of the cock and the other in the lever handle with which the cock is supplied. Fig. 2 is a side elevation 40 of the cock shown in Fig. 1, with the index members and adjuncts thereof in central vertical section. Fig. 3 is a detail in elevation of an oval index member for the cock body. Fig. 4 is a detail in elevation 45 of the index member for the handle. Fig. 5 is a plan view of the index member shown in Fig. 3. Fig. 6 is a perspective detail of another form of flat button. Fig. 7 shows a spherical index which might be used for 50 either the button or the handle.

The body of the cock is shown at 1, and at 2 is shown a concave seat for the support of the index member 4, which is commonly called a button, and is convex on its under

side if the seat is concave. The seat 2 is 55 bored and threaded, the button is bored centrally as shown at 4^a in Fig. 5, and a bolt 10 is inserted through the button and screwed into the bore of the seat until the button is clamped in place between the seat 2 and the 60 head 3 of the bolt. The button has different indications, such as words or signs, at different places around its perimeter, or around its edge if it be flat or flattened, but in any event they will not be clearly seen from 65 above. The words "Hot" and "Cold" are used in this instance, and either may be placed in position to confront the user. When the cock is used for hot water the word "Hot" is presented to the front or 70 placed in position to be readily seen, and when the cock is used for cold water the position of the button is reversed. If the cock had other uses and the button were provided with words or signs indicating such 75 uses, the operation would obviously be the same.

The handle 5 has a shoulder 6 forming a seat, and a bolt rod 7 extends from the shoulder and is threaded at its end. A rotary index member 8 is bored to slip over bolt 7, and is provided with indications such as the word "Hot" on its perimeter at one side and the word "Cold" at the other side. Finally a nut 9 is screwed on the threaded 80 end of the bolt 7 to clamp the member 8 against the shoulder or seat. The index member 8 form a part of the handle, its function is identical with the function of the button so far as its indexing characteristics go, and there is close mechanical similarity between the button and adjuncts and the rotatable index member of the handle and its adjuncts. In the case of the button, the nut element of the clamp is here shown 85 as formed in the cock body while the bolt element is separable from the cock; in the case of the handle, the bolt element of the clamp is here shown as formed on the handle while the nut element is separable. But all 90 that is involved is a reversal of mechanical elements, and in each form the idea of a nut-and-bolt clamp for the index member is retained. I do not confine myself to either 95 form in either position. Either the button or the handle index member would be sufficient on any one cock, but both are shown for the purpose of illustrating two embodi- 100 105

ments of the invention and thereby more clearly defining the principle involved.

The button in Fig. 6 is polygonal—showing that it might be square, triangular, or of other desired angular contour, so long as it has indications on the perimeter or edges which stand at right angles to the bore. In this view the button is designated as possibly having four indications around its perimeter, all different. The index in Fig. 7 is spherical, and could be used for the button 4 or the handle 8, according to its size and the length of its axial bore—showing that it might be round or rounded, ovoid or oval, so long as it had indications at the points which stand at right angles to the bore. In this view the same word, is designated on opposite sides of the perimeter, but, as stated above, that is immaterial. By 20 preference all words read around the axis and not parallel with it.

The advantages of a rotatable index when used in connection with a cock are many. These buttons are commonly made of pottery, suitably inscribed and with a highly glazed or porcelain surface, and the maker if given the necessary details for any type of button or handle need furnish only one with several indications for the cock to 30 which it is to be applied, rather than furnishing a plurality having different indications. The manufacturer of the cock need carry in stock but a single member, instead of a plurality having different indications, 35 and in assembling the parts it is immaterial what indications he leaves exposed. So also with the jobber and plumber. Finally, when the cock is set up for use, the workman without special tools can quickly adjust the index 40 so that the indication will agree with the service performed by the cock; and even afterward, if the user should, for instance, cut off hot water and desire the indication to be "Cold", he could change the index 45 himself.

My U. S. Patent No. 857957 covered a fixed cock body, an index button mounted thereon for rotary adjustment, and indications on its upper face at opposite sides of 50 its center so that either could be set toward the user and viewed from above. In the present case I hide the indication which is not to be read, by having it on the rearmost part of the index member where it is out 55 of sight of a user looking from above or from in front. Such part is, in the case of a flat or flattened member, at its edge, and in case of an axially elongated member is at the point most remote from its axis, and 60 in any event is at the true perimeter as distinguished from top or bottom or any face or side of the member. This idea, moreover, is applied in the present case to the swinging handle of the cock illustrated, and in that

respect differs further from my former construction which was not capable of that use. 65

In a companion application filed by me this day and bearing Serial Number 580,583, the index member is not bored but is clamped in place between the parts of a 70 separable housing, so that when the clamp is loosened the index or button can be shifted to expose through the clamp any one of several indications with which it is provided. In the present case the index member is rotatable in but one plane on its own axis. In each instance I have shown and described my index as used in connection with a cock where its indications are usually "Hot" or "Cold" or the like, but I do not mean to 80 limit the use of the invention to this art nor confine the indications to these words. 75

What is claimed as new is:

1. In a cock or the like, the combination with two clamping members forming part of 85 the cock; of an index member rotatably adjustable on its axis and held between the clamping members and provided at different places around its perimeter at points most remote from said axis with words or signs, 90 each indicating a use for the cock, all of which are exposed but only one at a time visible to the user.

2. In a cock or the like, the combination of a bolt element and a nut element constituting a clamp carried by the cock, and an index member axially bored to slip onto the bolt, the index member being adapted to be held clamped between the nut and the head of the bolt and provided on its perimeter with words or signs of different meaning reading around the axis, all of which are exposed but only one at a time visible to the user. 95

3. In a cock or the like, the combination 105 of a bolt element and a nut element constituting a clamp carried by the cock, and an index member bored to slip onto the bolt, the index member being rotatably adjustable and adapted to be held clamped between the 110 nut and the head of the bolt and provided around its extreme edge with indications, all of which are exposed but only one at a time visible to the user.

4. In a cock or the like, the combination 115 with a seat on the cock, and a rotatable index button having an axial bore and provided around its perimeter with indications of which but one at a time confronts the user and the others are hidden from him; of 120 a nut-and-bolt clamp passing through said bore and holding the button on the seat but permitting its adjustment around its axis.

5. The combination with a cock having a button seat bored and threaded, and a screw 125 whose tip is adapted to engage said threaded bore; of a flattened index button provided around its edge with different indications.

any of which may confront the user while
the others are hidden from him, said button
being bored for the passage of the shank of
the screw, capable of adjustment on it, and
5 clamped between its head and said seat, sub-
stantially as described.

In testimony whereof I have hereunto

subscribed my signature this the 22nd day of
June, A. D. 1907.

HENRY MUELLER.
